CLAIM

The ornamental design for container having multiple compartments, as shown and described.

DESCRIPTION

FIG. 1 is an exploded perspective view of a container having multiple compartments according to the present design.

FIG. 2 is an exploded side view of the container having multiple compartments of FIG. 1 when the second container is open.

FIG. 3 is an exploded side view of the container having multiple compartments of FIG. 1 when the second container is closed.

FIG. 4 is a top perspective view of the container having multiple compartments of FIG. 1 when the first and the second container are assembled.

FIG. 5 is a side view of the container having multiple compartments of FIG. 4.

FIG. 6 is a bottom perspective view of the container having multiple compartments of FIG. 4.

FIG. 7 is a top view of the second container of FIG. 1 when the second container is closed.

FIG. 8 is a top perspective view of the second container of FIG. 7.

FIG. 9 is a side view of the second container of FIG. 7.

FIG. 10 is a bottom perspective view of the second container of FIG. 7.

FIG. 11 is a top view of the second container of FIG. 1 when the second container is open.

FIG. 12 is a top perspective view of the second container of FIG. 11.

FIG. 13 is a side view of the second container of FIG. 11; and,

FIG. 14 is a bottom perspective view of the second container of FIG. 11.
